ABSTRACT

A threaded insert for an air field light fixture. The threaded insert is manufactured to repair or replace the threading in such light fixtures by providing the airfield light fixture with a replacement threaded insert to permit quick and simple repair upon the occurrence of a broken bolt or stripped threading.

THREADED INSERT FOR AN AIRFIELD LIGHT FIXTURE

RELATED APPLICATIONS AND INCORPORATION BY REFERENCE

This application claims benefit and priority to U.S. Provisional patent application Ser. No. 63/441,522, filed Jan. 27, 2023. The foregoing application is hereby incorporated by reference.

FIELD OF DISCLOSURE

The present disclosure generally relates to a threaded insert for an airfield light fixture.

BACKGROUND

Inset light fixtures have long been used at airports to provide lighting for both airport runways and taxiways. Typically each light fixture includes a container which houses electrical components and is embedded into the concrete. Typically each light fixture includes a cover which is mountable to the top of the container with plurality of bolts which extend into threaded openings in the container.

Due to its exposure to the elements, the light fixture and its corresponding bolts undergo a significant amount of wear and tear. Bolts and light fixtures often rust or deteriorate in the normal course of operation. In addition, maintenance of these light fixtures requires the removal of the bolts in order to gain access to the container and electrical components. A common problem with these light fixtures is that the bolts rust and break within the threaded opening of the container or the bolts strip the threading upon their removal.

In such case, the threaded openings of the container are blocked and/or damaged and require repair before the light fixture can be resecured within the pavement. This often requires broken bolts to be removed and damaged threadings be rethreaded on site.

U.S. Pat. No. 6,550,931 discloses a threaded insert for use with an airfield light fixture. However, this patent discloses removable inserts that are used in connection with each and every bolt of the device. This prior reference discloses a base can which specifically requires the inserts in the disclosure in order to function. The disclosure of the '931 patent is not directed toward an insert that can replace any stripped threading in airfield light fixtures. Instead the '931 Patent is directed to inserts which are specially created for the disclosed light fixture.

A long-felt, but unmet, need exists for a simple and easy way to re-thread or repair the threaded holes within any air field light fixture container.

SUMMARY OF DISCLOSURE

This summary is provided to introduce a selection of concepts in a simplified form further described in the detailed description of the disclosure. This summary is not intended to identify key or essential inventive concepts of the claimed subject matter, nor is it intended for determining the scope of the claimed subject matter.

A long-felt, but unmet, need exists for a simple and easy method and device to re-thread and repair damaged threadings within an airfield light fixture.

According to the present invention, this object is achieved by providing the airfield light fixture with a replacement

threaded insert to permit quick and simple repair upon the occurrence of a broken bolt or stripped threading.

Embodiments of the present disclosure address one or more of the disadvantages and problems discussed above.

BRIEF DESCRIPTION OF THE DRAWINGS

FIG. 1 depicts a perspective view of the threaded insert.

FIG. 2 depicts a second perspective view of the threaded insert.

FIG. 3 depicts a side view of the threaded insert.

FIG. 4 depicts a top view of the threaded insert.

FIG. 5 depicts a second side view of the threaded insert.

FIG. 6a depicts the container portion of a light fixture base can embedded in pavement.

FIG. 6b depicts a close up view of a portion of the light fixture base can of FIG. 6a.

FIG. 7 depicts the container and cover of the airfield light fixture bolted into the pavement.

FIG. 8 depicts an exploded view of the airfield light fixture, a bolt, and threaded insert.

FIG. 9 depicts a flow diagram of the steps of using the threaded insert.

DETAILED DESCRIPTION

This disclosure as a whole may be best understood by reference to the following detailed description when read in conjunction with the accompanying drawings, drawing descriptions, abstract, background, field of disclosure, and associated headings. Identical reference numbers when found on different figures identify the same elements or a functionality equivalent element. The elements listed in the abstract are not referenced but nevertheless refer by association to the elements of the detailed description and associated disclosure.

The Insert

FIGS. 1-5 depict a threaded insert 100. The insert 100 has a top end 102, bottom end 104, and side wall 106 extending between the top end 102 and bottom end 104. The insert 100 is a generally cylindrical member with a hole 108 extending longitudinally therethrough. In an embodiment, the hole 108 includes an internal threading. In alternative embodiment, the hole 108 does not comprise internal threading.

As depicted in FIGS. 1-5, a lip 116 projects radially and outwardly from the bottom end 104 of the insert 100. In the preferred embodiment, the lip 116 is integral with and comprised of the same material as the sidewall 106.

As depicted in FIGS. 1-5, the top end 102 of the insert 100 is tapered 110, which assists with installing the insert 100 into the airfield light fixture 200. In an alternative embodiment, the top end 102 of the inset does not include a tapered portion. A plurality of protrusions 114 extend radially from the exterior side wall 106 of the insert 100 which assists with securing the insert 100 into place. In the embodiment depicted in FIGS. 1-5, the protrusions 114 comprise a plurality of splines.

In the preferred embodiment, and as depicted in FIG. 1, the interior side wall 112 of the insert 100 is threaded to receive bolts and secure the cover of the airfield light fixture to the container of the airfield light fixture.

In a preferred embodiment, the tapered portion 110 forms a five degree angle with the side wall 106 of the insert 100. In the preferred embodiment, the tapered portion 110 includes a plurality of protrusions 114 of similar shape as the

protrusions 114 extending from the exterior side wall 106. In the preferred embodiment, the tapered portion is about 0.0750 in. in length. In alternative embodiments, other configurations of the tapered portion are considered.

The insert 100 may be manufactured to comply with an airfield light container 200 fixture having holes of any size. In a first embodiment of the insert 100, the insert has a length of about 0.4550 in. from the lip 116 to the top end 102, an outside sidewall 106 diameter of about 0.5 in. (without the protrusions 114), a protrusion extending the length of up to 0.036 in. away from the side wall 106, and an interior sidewall 106 diameter of about 0.375 in. In this embodiment, the diameter of the lip 116 is approximately 0.6875 in. and has a thickness of about 0.0800 in.

In a second embodiment of the insert 100, the insert has a length of about 0.8300 in. from the lip 116 to the top end 102, an outside sidewall 106 diameter of about 0.5 in. (without the protrusions 114), a protrusion extending the length of up to 0.036 in., and an interior sidewall thickness of about 0.375 in. In an alternative embodiment, the diameter of the lip 116 is approximately 0.6875 in. and has a thickness of about 0.0787 in.

In another embodiment, the outside sidewall 106 has a diameter of about 10 mm. Other embodiments are considered which allow for universal installation of the insert 100 into airfield light fixtures 200.

The insert 100 of the present disclosure is comprised of thermoplastics, composites, metals, or the like (including but not limited to Carbon Steel and/or Stainless Steel). Many inserts currently in use in the art are made from Carbon Steel. In a preferred embodiment, the insert 100 of the present disclosure is made from 316 Stainless Steel.

Inserts currently in use with airfield light fixtures do not include a tapered barrel. In the preferred embodiment of the present disclosure, the barrel of the insert 100 is tapered to assist with drilling the insert 100 into the container of the airfield light fixture 200.

Inserts currently in use in the art typically have an exterior sidewall diameter of $1\frac{1}{32}$ " (without protrusions). In an embodiment of the present disclosure, the insert 100 has an exterior sidewall thickness of $\frac{1}{2}$ " (excluding protrusions 114). This provides additional space for protrusions 114 and allows the inserts 100 to include protrusions 114 with longer splines. In effect, the longer splines prevent stripping and lock the insert 100 into the airfield light fixture 200 more effectively.

In the preferred embodiment of the present disclosure, the protrusions 114 extend up to 0.036 in. from the exterior sidewall 106 of the insert 100. The protrusions 114 of the present disclosure cut deeper and are spread wider apart than the inserts 100 in the prior art. The insert 100 of the present disclosure locks more effectively into the airfield light fixture 200 and prevents rotation of the insert 100 when torquing a bolt. The insert 100 of the present disclosure also prevents stripping or destruction of the hole 210 in the airfield light fixture 200 (i.e., it prevents a user from making the hole 210 larger than the insert 100 itself during installation).

The Airfield Light Fixture

FIGS. 6 and 7 depict a standard airfield light fixture 200. An airfield light fixture 200 is typically installed in the ground 202 such as the pavement of an airfield runway. The light fixture 200 generally comprises a base can 204 with a container 206 and flange 208 portion. The container portion 206 includes a generally cylindrical side wall with an upper

and lower end. A flange 208 is mounted on the upper end of the side wall and extends outwardly and radially therefrom. A plurality of threaded holes 210 are spaced apart along the perimeter of the flange 208, the holes 210 are often designed with threading 216 to receive a standard bolt 214.

Each base can 204 has a corresponding cover 212 which is generally circular in shape and sized to cover the open upper end of the base can 204. The cover 212 includes a plurality of holes positioned for alignment with the threaded holes 210 in the base can 204.

The cover 212 is secured to the base can 204 by aligning the holes of the cover and the holes 210 and securing said bolts 214 into the holes 210.

15

Method of Use

FIG. 8 depicts an exploded view of the airfield light fixture, a bolt, and threaded insert. FIG. 9 depicts a flow diagram of the method of using the threaded inserts 100 of the present disclosure 900. Over time, the threading 216 within the holes 210 may become stripped or damaged. The threaded inserts 100 allow a user to repair or replace the threading within a light fixture 200 quickly and easily.

In a first step 902, a user may remove the bolts 214 from the holes 210 of the airfield light fixture. In a second step 904, a user removes the cover/lid 212 from the top of the base can 204 of the airfield light fixture. The base can 204 is removable from the ground and is not fixed to the airfield runway 202. Once the lid 212 is removed, a user can access the interior of the airfield light fixture to make any necessary repairs to the light fixture itself or to the electrical components therein. In a third step, the user inspects the holes 210 to determine whether the threading 216 has been damaged.

If the threading has been damaged, the user proceeds to a fourth step 908 and drills a threaded insert 100 into any holes 210 having damaged threads 216. In a preferred embodiment, the threaded insert 100 is drilled upward from the bottom of each hole 210. In a fifth step 910, the user places the cover/lid 212 on top of the base can 204 of the light fixture. In a final step 912, the user can reapply the bolts 214 to the holes 210 (at least some of which now include the threaded inserts 100) to secure the light fixture in place 912.

If the threading 216 within the holes 210 has not been damaged or stripped, the user may elect to simply reattach the lid to the light fixture 910 and refasten the bolts 214 to the holes 210. In alternative embodiments, even if the threading 216 of the holes 210 has not been damaged, a user may elect to apply the threaded inserts 100 to the holes.

The walls of the threaded insert 106 include a plurality of protrusions 114 (i.e., ribbed splines). The walls of the threaded insert 106 (with the ribbed splines) are slightly larger in diameter than the holes 210. When the insert is drilled into the hole 210, the splines cut into the 208 and lock the insert 100 in place. Once the insert 100 is in place, a user can secure a bolt 214 within the interior threading 112 of the insert 100. The lip 116 of the insert 100 contacts the lower face of the flange 208 to prevent the insert from being removed through the upper face of the flange 208 if the user later tries to remove the bolt 214.

It is understood that the preceding is merely a detailed description of some examples and embodiments of the present invention and that numerous changes to the disclosed embodiments may be made in accordance with the disclosure made herein without departing from the spirit or scope of the invention. The preceding description, therefore, is not meant to limit the scope of the invention, but to

5

provide sufficient disclosure to allow one of ordinary skill in the art to practice the invention without undue burden.

What is claimed is:

1. A threaded insert for an airfield light fixture comprising: a top end and a bottom end; a cylindrical wall running between the top and bottom ends of the threaded insert; a lip integral with the cylindrical wall proximate the bottom end of the threaded insert, wherein the lip has a diameter greater than the diameter of the cylindrical wall; an opening proximate the top end of the threaded insert and extending throughout the cylindrical wall to form a cavity between the interior of the cylindrical wall and the lip; a plurality of protrusions extending radially from the exterior of the cylindrical wall; and a tapered portion proximate the end of the cylindrical wall opposite the lip, wherein the cavity extending throughout the cylindrical wall and tapered portion has a substantially uniform radius and the exterior of the tapered portion forms an angle with the plane of the cylindrical wall; and wherein the interior of the cylindrical wall is threaded. 25
2. The threaded insert of claim 1, wherein the plurality of protrusions extending radially from the exterior of the cylindrical wall comprise a plurality of splines, wherein a base portion of each of the plurality of splines integral with the cylindrical wall is greater in thickness than a top end of each of the plurality of splines extending from the cylindrical wall. 30
3. The threaded insert of claim 2, wherein the plurality of splines extend up to approximately 0.036 in. from the cylindrical wall. 35
4. The threaded insert of claim 1, wherein the tapered portion forms between a two to six degree angle with the plane of the cylindrical wall.
5. The threaded insert of claim 1, wherein the tapered portion forms a five degree angle with the plane of the cylindrical wall. 40
6. The threaded insert of claim 1, wherein the diameter of the cylindrical wall is approximately 0.5 in.
7. The threaded insert of claim 1, wherein the length from the top end of the threaded insert to the bottom end of the threaded insert is approximately between 0.455 in. to 0.83 in. 45
8. The threaded insert of claim 1, wherein the lip comprises a diameter of approximately 0.6875 in. and a thickness of approximately between 0.0787 in. to 0.08 in. 50
9. The threaded insert of claim 1, wherein the cavity between the interior of the cylindrical wall and the lip has a diameter of approximately 0.375 in.
10. An airfield light fixture apparatus comprising: a cylindrical light fixture base can manufactured to be 55 embedded into an airfield runway, the base can comprising a container portion to be embedded in the ground and a flange portion; the container portion comprising a cylindrical side wall with an open top end and a closed bottom end; the flange portion extending radially from the top end of the container portion, wherein a plurality of threaded holes are spaced around the flange; a cylindrical cover manufactured to cover the top end of the container portion, wherein the cylindrical cover comprises a plurality of holes positioned to align with the holes of the flange portion; 60 65

6

- a series of fasteners to secure the cylindrical cover to the cylindrical light fixture base can; and
- a threaded insert applied to the plurality of threaded holes wherein the threaded insert comprises: a top end and a bottom end; a cylindrical wall running between the top and bottom ends of the threaded insert; a lip integral with the cylindrical wall proximate the bottom end of the threaded insert, wherein the lip has a diameter greater than the diameter of the cylindrical wall; an opening proximate the top end of the threaded insert and extending throughout the cylindrical wall to form a cavity between the interior of the cylindrical wall and the lip; a plurality of protrusions extending radially from the exterior of the cylindrical wall; and a tapered portion proximate the end of the cylindrical wall opposite the lip, wherein the cavity extending throughout the cylindrical wall and tapered portion has a substantially uniform radius and the exterior of the tapered portion forms an angle with the plane of the cylindrical wall; and wherein the interior of the cylindrical wall is threaded. 25
11. The airfield light fixture apparatus of claim 10, wherein the flange comprises a top face and a bottom face and the threaded insert is applied to the plurality of threaded holes such that the lip is flush with the bottom face of the flange. 30
12. The airfield light fixture apparatus of claim 11, wherein the plurality of protrusions comprise a plurality of splines wherein the base of the spline extending from the cylindrical wall is greater in thickness than the top of the spline. 35
13. The airfield light fixture apparatus of claim 12, wherein the diameter of the plurality of splines is greater than the diameter of the plurality of threaded holes. 40
14. The airfield light fixture apparatus of claim 13, wherein the splines extend up to approximately 0.036 in. from the cylindrical wall. 45
15. The airfield light fixture apparatus of claim 13, wherein the fasteners are secured within the cavity of the threaded insert. 50
16. The airfield light fixture apparatus of claim 10, wherein the tapered portion forms a five degree angle with the plane of the cylindrical wall. 55
17. A method of repairing threading of an airfield light fixture comprising the steps of: removing a plurality of fasteners from an airfield light fixture apparatus comprising a cover, a base can having a flange which comprises a plurality of threaded holes, and the plurality of fasteners; removing the cover of the airfield light fixture apparatus; inspecting the threaded holes within the flange portion of the light fixture apparatus; clearing the threaded holes of any debris; drilling a plurality of threaded inserts into the plurality of threaded holes within the flange portion of the airfield light fixture; replacing the cover of the airfield light fixture apparatus; and reapplying the fasteners to the cover of the airfield light fixture apparatus. 60 65 70 75 80 85 90

18. The method of claim 17, wherein the plurality of threaded inserts applied to the plurality of threaded holes comprise:

- a top end and a bottom end;
- a cylindrical wall running between the top and bottom ends of the threaded insert;
- a lip integral with the cylindrical wall proximate the bottom end of the threaded insert, wherein the lip has a diameter greater than the diameter of the cylindrical wall;
- an opening proximate the top end of the threaded insert and extending throughout the cylindrical wall to form a cavity between the interior of the cylindrical wall and the lip;
- a plurality of protrusions extending radially from the exterior of the cylindrical wall; and
- a tapered portion proximate the end of the cylindrical wall opposite the lip, wherein the cavity extending throughout the cylindrical wall and tapered portion has a substantially uniform radius and the exterior of the tapered portion forms an angle with the plane of the cylindrical wall.

19. The method of claim 18 wherein the step of drilling a plurality of threaded inserts into the plurality of threaded holes within the flange portion of the airfield light fixture further comprises:

- aligning the top end of the threaded insert with the plurality of threaded holes along the bottom face of the flange; and
- providing sufficient force to wedge the threaded insert into the threaded holes within the flange.
